[57] CLAIM

The ornamental design for a magnetic door holder, as shown and described.

DESCRIPTION

FIG. 1 is an exploded perspective view of the female element of a magnetic door holder showing my new design; shown separately for ease of illustration;

FIG. 2 is an exploded perspective view of the male element; also, shown separately for ease of illustration;

FIG. 3 is a side elevational view of FIG. 1;

FIG. 4 is a bottom plan view of FIG. 1;

FIG. 5 is a top plan view of FIG. 2 the bottom being flat;

FIG. 6 is a side elevational view of FIG. 2, the side opposite being a smooth surface;

FIG. 7 is a perspective view of the door stop shown separately for ease of illustration;

FIG. 8 is a perspective view thereof.

FIG. 7

FIG. 8
